UNITED STATES PATENT OFFICE.

FRANCIS L. CLARK, OF PITTSBURG, PENNSYLVANIA, ASSIGNOR TO THE AMERICAN BRAKE COMPANY, OF ST. LOUIS, MISSOURI, A CORPORATION OF MISSOURI.

AUTOMATIC SLACK-ADJUSTER.

SPECIFICATION forming part of Letters Patent No. 728,443, dated May 19, 1903.

Application filed September 6, 1901. Serial No. 74,537. (No model.)

To all whom it may concern:

Be it known that I, FRANCIS L. CLARK, a citizen of the United States, residing at Pittsburg, county of Allegheny, State of Pennsylvania, have invented or discovered a certain new and useful Improvement in Automatic Slack-Adjusters for Brakes, of which improvement the following is a specification.

- My invention relates to slack-adjusters for railway-brakes, and particularly to that class of brakes in which a fluid-pressure brake-cylinder is employed; and the object of my invention is to provide an adjustable connection between the brake-piston and the brake-rigging whereby the slack of the brake-rigging, due to the wear of the brake-shoes and other causes, will be automatically taken up, so as to maintain a practically constant and uniform travel of the brake-piston.
- My invention consists in providing, in combination with the brake-piston, an extensible mechanism adapted to receive the push-bar of the brake-rigging; and it also consists in forming said extensible mechanism of a tubular adjusting-screw connected to the brake-piston through a ratchet-nut and pawl mechanism, whereby the position of the screw with respect to the brake-piston may be automatically adjusted.
- My invention further consists in certain combinations and arrangement of parts, all as hereinafter more fully set forth.

In the accompanying drawings, Figure 1 is a longitudinal section of a brake-cylinder and my improved construction applied thereto; Fig. 2, a plan view of the rear head of a brake-cylinder and the slack-adjusting mechanism, a portion of the cam-plate being broken away to more clearly show the construction; Fig. 3, an end view, the hand-wheel being removed and a part of the outer nut being broken away to show the ratchet-nut; Fig. 4, a transverse section taken on the line xx of Fig. 1; Fig. 5, a vertical section showing a modified form of brake-cylinder and slack-adjusting mechanism; Fig. 6, a horizontal section taken on the line yy of Fig. 5; Fig. 7, a vertical section taken on the line zz of Fig. 6; Fig. 8, a vertical section of the lower end portion of

the brake-cylinder, showing the key mechanism for preventing the rotation of the screw during the automatic adjustment of the slack; Fig. 9, a fragmentary perspective view showing the connection between the same plate and the ratchet-ring, and Fig. 10 a detail sectional view taken on the line ww of Fig. 8.

Referring now more particularly to Sheet 1 of the drawings, the brake-cylinder 1, piston 2, and spring 3 (shown in Fig. 1) may be of the ordinary or any preferred construction. The piston is provided with the hollow or tubular piston-rod 4, which extends out through the rear head 7 of the brake-cylinder and in which is located the hollow screw 5, adapted to receive the end of the thrust-bar 19 of the brake-rigging. On the hollow piston-rod is located the split sleeve or bush 6, which is made in two parts and securely clamped onto the rod by means of bolts 8. This sleeve is provided with a key 9, which works in a corresponding notch or seat in the cylinder-head 7 and prevents rotary movement of the sleeve and piston-rod. The ratchet-nut 13 is rotatably mounted on the end of the hollow piston-rod and has a rim 75 engaging a bearing in the split sleeve 6, the interior of the nut being threaded to engage the thread of the hollow screw 5. On the ratchet-nut is rotatably mounted a ring 14, carrying the pawl 17, pivoted thereto and adapted to engage the teeth of the ratchet-nut. Another pawl 25, pivoted on a lug 26, projecting from the split sleeve 6, engages the ratchet-nut to prevent a backward rotation of the same. Springs 27 and 28 may be provided to force the respective pawls into engagement with the teeth of the ratchet-nut. The ring is held on the ratchet-nut by a nut 15, and the projecting end of the hollow screw is provided with a hand-wheel 18, by means of which the screw may be returned to its inner position when it becomes necessary to reset the mechanism. In order to prevent the screw from turning during the automatic operation of adjusting the slack, I provide a key 20, which is carried by the trigger-lever 22, pivoted to the lugs 21 on the split sleeve 6, the key extending through the openings in

the sleeve and piston-rod and into the groove 24, formed in the thread of the hollow screw 5. A spring 23 normally presses the key 20 into the said groove; but when the screw is to be turned back by hand to reset the device the trigger-lever is pushed in against its spring to raise the key out of the groove 24 and allow a free adjustment of the screw by means of the hand-wheel 18. The pawl-ring 14 has a projection or pin 16, extending into the cam slot or groove 29 of the cam-plate 10. This cam-plate may be supported in position by any convenient means; but as a preferred construction I have shown the same secured to the cylinder-head 7 by means of a cap-screw 12, passing through a slot 11 in the cam-plate, which allows for the adjustment of the position of the cam-groove with respect to the brake-cylinder. The cam-plate is so adjusted that the pin 16 reciprocates in the straight portion of the groove during the normal travel of the brake-piston; but when, owing to the wear of the brake-shoes and stretching of the brake-rigging, the travel of the brake-piston becomes greater than desired the projection or pin 16 of the pawl-ring enters the inclined or curved portion of the cam-groove and turns the ring upon the ratchet-nut, thus carrying the pawl 17 backward over one or more teeth of the ratchet-nut, according to the length of the stroke of the brake-piston. Then when the brakes are released and the piston-spring moves the parts positively back to release position the ratchet-nut will be rotated forward one or more notches, thus adjusting the hollow screw outward toward the push-bar and taking up the slack. The pawl 25, which is pivoted on the non-rotatable split sleeve 6 and is in constant engagement with the teeth of the ratchet-nut, prevents the ratchet-nut from turning during the outward movement of the piston, and this is an important feature, since if the ratchet-nut should rotate with the pawl-ring on the outward movement of the piston the slack would be increased instead of diminished. It will also be noticed that the adjusting mechanism is directly secured to the hollow piston-rod, so that it moves positively with the brake-piston, and the operation of taking up the slack is not dependent upon the mere relaxation of the brake-rigging, but is positively performed by the force of the spring of the brake-piston. This construction forms what is practically an extensible hollow piston-rod secured to the brake-piston and adapted to receive the loosely-fitting push-bar of the brake-rigging.

In Figs. 5 to 10 of the drawings I have shown a compact form of my invention, in which all the parts of the adjusting mechanism are located inside the brake-cylinder, and such a construction is adapted to be used when it is necessary to economize the space occupied by the brake-cylinder. In this modified construction the split sleeve 6^a is secured directly to the piston by flanges and

screws or other means and has a projection 9^a, extending into the groove formed by the two guide-lugs 30, carried by the inner surface of the rear cylinder-head 7^a. The piston 2^a of the brake-cylinder 1 may be provided with a cylindrical recess 31 in its rear face in line with the opening of the split sleeve 6^a, through which extends the hollow adjusting-screw 5^a. The ratchet-nut 13^a is internally threaded to engage the threads of the adjusting-screw and has a rim and groove forming a rotary bearing in the split sleeve 6^a, which prevents any longitudinal movement of the ratchet-nut relative to the piston. On the ratchet-nut is rotatably mounted the pawl-ring 14^a, carrying the spring-pressed pawl 17^a, pivoted on the lug 32, while the fixed spring-pressed pawl 25^a is pivotally supported on the lug 26^a of the split sleeve 6^a, and both pawls engage the teeth of the ratchet-nut, as in Figs. 1 to 4. The rear head 7^a of the brake-cylinder is formed with an inner cylindrical extension 37, outside of which is an annular space for the spring 3, and the rear end of the cylinder-head is provided with an opening 36 for the trigger-lever 22^a and a lug 33, having a slot through which the key 20^a extends into the groove or key-seat 24^a of the adjusting-screw 5^a. The trigger-lever extends through the opening 36 between lugs 34 and bears at one point against the end of the cap-screw 35, which carries the spring 23^a, that normally holds the key 20^a in engagement with the key-seat 24^a and prevents rotary movement of the adjusting-screw. On the ratchet-nut is pinned or otherwise secured the washer 15^a, the outer perimeter of which is provided with a projecting lug 38, adapted to engage the inner end of the trigger-lever when the latter is operated to withdraw the key 20^a from the groove 24^a of the adjusting-screw. When it becomes necessary to reset the adjusting-screw, the outer end of the trigger-lever may be readily raised, withdrawing the key 20^a from its seat in the adjusting-screw, and at the same time the inner end of the trigger-lever bears upon the outer perimeter of the washer 15^a, so that the lug 38 will engage the trigger-lever and prevent the rotation of the washer and ratchet-nut when the screw is turned back to its inner position by means of the hand-wheel. The operation of this form of my device in automatically taking up the slack is substantially the same as that already described with reference to Figs. 1 to 4 of the drawings. The cam-groove 29^a in the cam-plate is so formed that an excessive movement of the brake-piston results in the backward rotation of the pawl-ring and pawl 17^a on the teeth of the ratchet-nut. Then upon release of the brakes the ratchet-nut is rotated on the adjusting-screw, and since the latter is prevented from turning it will be adjusted outward to eliminate the slack of the brake-rigging. It will be seen that this

is substantially the same construction as that shown on Sheet 1 of the drawings—that is, it constitutes an extensible hollow piston-rod comprising a hollow adjusting-screw connected to the brake-piston through a pawl-and-ratchet mechanism, whereby the position of the screw with respect to the brake-piston may be adjusted.

Having now described my invention, what I claim as new, and desire to secure by Letters Patent, is—

1. A brake-piston having a hollow piston-rod formed in sections, one of said sections being adjustable and adapted to receive the push-bar of the brake-rigging.

2. The combination of a brake-piston having an extensible rod secured thereto adapted to receive the push-bar of the brake-rigging, and means for adjusting the length of the rod.

3. In a brake slack-adjuster, the combination with a brake-piston of a hollow adjusting-screw adapted to receive the push-bar of the brake-rigging, said screw being connected to the piston through a ratchet mechanism whereby the position of the screw relative to the brake-piston may be adjusted.

4. In a brake slack-adjuster, the combination with a brake-piston having an extensible rod secured thereto including an adjusting-screw, of a ratchet-nut for the screw, and means for preventing the backward rotation of the ratchet-nut.

5. In a brake slack-adjuster, the combination of a brake-piston, an adjusting-screw secured thereto and adapted to operate the push-bar of the brake-rigging, a ratchet-nut, a pawl for giving a forward rotation to the ratchet-nut, and another pawl for preventing a backward rotation of said nut.

6. In a brake slack-adjuster, the combination with a brake-piston having an extensible rod including an adjusting-screw, of a ratchet-nut and pawl mechanism for adjusting the screw, and a key for preventing the rotation of the screw.

7. In a brake slack-adjuster, the combination with a brake-piston, of a sleeve movable therewith, an adjusting-screw, means for preventing rotation of the sleeve, and a ratchet-

nut rotatably connected to said sleeve for adjusting the screw.

8. In a brake slack-adjuster, the combination with a brake-piston of a sleeve movable therewith, an adjusting-screw, a ratchet-nut for the screw rotatably mounted in the sleeve, means for preventing rotation of the sleeve, and a pawl carried by the sleeve for preventing backward rotation of said nut.

9. In a brake slack-adjuster, the combination with a brake-piston having an extensible rod including an adjusting-screw, a ratchet-nut for adjusting the screw, a key for normally preventing rotation of the screw and hand-operated means for withdrawing the key and turning the screw back to its original position in the nut.

10. In a brake slack-adjuster, the combination with a brake-piston having an extensible rod including a ratchet-driven screw, of a key engaging the screw to prevent rotation thereof, and a trigger-lever for operating said key.

11. In a brake slack-adjuster, the combination of a brake-piston having a tubular rod and a split sleeve clamped on said rod, of an adjusting-screw in said tubular rod and a ratchet-nut for adjusting said screw.

12. In a brake slack-adjuster, the combination of a brake-piston, a sleeve movable therewith, means intermediate the sleeve and cylinder-head for preventing rotation of the sleeve, an adjusting-screw and a ratchet-nut engaging said screw and rotatably mounted in said sleeve.

13. In a brake slack-adjuster, the combination of a brake-cylinder having an extensible hollow piston-rod formed in sections, one section comprising a hollow adjusting-screw, of a ratchet-nut for said screw, a pawl-ring mounted on said nut and having a pawl engaging the teeth of the ratchet-nut, and a cam-plate adapted to oscillate the pawl-ring upon excessive travel of the brake-piston.

In testimony whereof I have hereunto set my hand.

FRANCIS L. CLARK.
